UNITED STATES PATENT OFFICE

DONALD H. WEST, OF NEW LONDON, CONNECTICUT, ASSIGNOR TO THE LAPOINTE MACHINE TOOL COMPANY, OF HUDSON, MASSACHUSETTS, A CORPORATION OF MAINE

HYDRAULIC PULL BUSHING FOR BROACHING MACHINES

Application filed August 8, 1929. Serial No. 384,393.

This invention relates to a pull bushing particularly designed for use in a broaching machine in which the return movement of the broach is accomplished at increased speed by the application of hydraulic pressure.

It is the object of my present invention to provide means by which the application of hydraulic pressure also unlocks or releases the broach at the beginning of the return stroke, so that the broach may be removed during or after the return stroke, as desired by the operator.

My invention further relates to arrangements and combinations of parts which will be hereinafter described and more particularly pointed out in the appended claims.

A preferred form of the invention is shown in the drawings in which

Fig. 1 is a side elevation of my improved hydraulic pull bushing;

Fig. 2 is a plan view thereof;

Fig. 3 is an end elevation, looking in the direction of the arrow 3 in Fig. 1, and

Figs. 4 and 5 are detail views of certain parts to be described.

Referring to the drawings, I have shown my improved pull bushing as comprising a head 10 formed in two parts separable along longitudinal lines and secured together by clamping screws 11. The head 10 is provided with a shank 12 adapted to be inserted in a threaded opening in a cross head 14 and retained therein by a lock nut 15. The end of a tubular pull shaft 16 is also threaded in the cross head 14 and is retained in position by a lock nut 17.

A plug 18 is secured in the end of the pull shaft 16 and in effect forms one end of a pressure cylinder 20 within the shaft 16. The shank 12 of the head 10 is provided with an axial recess in which a push rod 22 is slidable, and the plug 18 in the shaft 16 is also provided with an axial recess 24 and a conical end opening 25 to receive a headed stud or sliding plunger 27.

A cross pin 30 is pivoted at 31 in the head 10 and is provided with a ball-shaped bearing portion 32 and with a handle portion 33. The ball-shaped portion 32 is positioned in an opening 35 in a cam plate 36 (Fig. 5), 50 slidably secured to the top of the head 10 by studs 37. The plate 36 is provided with inclined cam surfaces 38 adapted to engage studs 40 mounted in swinging arms 41 and projecting downward therefrom. A spring 42 is connected between the studs 40 and draws the arms 41 yieldingly toward each other.

The arms 41 are non-rotatably secured to the upper end of cross shafts 44 (Fig. 4) each 60 having dogs 45 formed integral therewith. These dogs 45 are positioned to swing transversely in openings 46 extending transversely through the head 10.

The head 10 is provided with an axial opening 65 to receive the shank of a broach B, and ends of the dogs 45 normally extend into recesses 50 in the sides of the shank broach, with the ends of the dogs positioned to engage the under side of the head 52 of the broach at 70 the beginning of the working stroke.

As the broach reaches its extreme right hand position at the end of the working stroke, (as viewed in the drawings), hydraulic pressure is applied in the cylinder 20 75 to reverse the direction of movement and actuate the broach at increased speed on its idle or return stroke.

As soon as pressure is applied in the cylinder 20, the piston 27 is forced to the left in 80 Fig. 1, engaging the plunger 22 and forcing the same against the cross pin 30, which in turn moves the cam plate 36 and causes the same to engage and forcibly separate the studs 40 and arms 41. Such movement of the 85 arms swings the dogs 45 outward to inoperative position.

During the final portion of the movement of the cam plate 36, the studs 40 engage the parallel outer side surfaces of the plate 36 90

and the dogs are thus locked in inoperative position during the removal and replacement of the broach. After the broach is replaced and the pressure is relieved in the cylinder 20, the dogs 45 may be released by manual return movement of the cross pin 30, applied to the handle portion 33.

I have thus provided mechanism by which the broach is automatically released by the same hydraulic pressure which causes return movement thereof and by which the broach remains in unlocked position until manual withdrawal of the cam plate 36. The plate 36 may also be moved manually to separate the dogs and release the broach whenever desired.

It will be noted that the broach is unlocked during the entire return movement thereof, so that the operator may remove the broach before the return movement is completed if he so desires.

Having thus described my invention and the advantages thereof, I do not wish to be limited to the details herein disclosed, otherwise than as set forth in the claims, but what I claim is:—

1. In a broaching machine, a pull bushing comprising a head, a pair of broach-engaging dogs pivoted in said head, means to move said dogs toward each other to engage the broach, arms fixed with respect to said dogs, studs in said arms, and a double faced cam plate slidably between said studs and effective to separate said dogs and to thereby release a broach when moved relative to said head. —

2. In a broaching machine, a pull bushing comprising a head, a pair of broach-engaging dogs pivoted in said head, means to move said dogs toward each other to engage the broach, arms fixed with respect to said dogs, studs in said arms, and a double faced cam plate slidably between said studs and effective upon movement relative to said head to separate said dogs and to thereby release the broach and said cam plate having an additional portion effective to lock said dogs in separated position.

3. In a broaching machine, a pull bushing comprising a head, a pair of broach-engaging dogs pivoted in said head, means to move said dogs toward each other to engage the broach, a cam plate slidably mounted on said head and effective to separate said dogs and thereby release the broach, automatic means including a member movable in said head upon the application of pressure to said member and effective by such movement to slide said cam plate on said head in one direction to separate said dogs, and manual means to return said plate to inoperative position.

4. In a broaching machine, a pull bushing, broach-engaging dogs mounted in said bushing, a hollow cylindrical pull shaft connected to said bushing and in which hydraulic pressure may be applied to produce a quick return

stroke of said shaft and bushing, a piston slidable axially in said shaft upon the application of hydraulic pressure therein to actuate the dogs, and connections between said piston and said dogs whereby said dogs are automatically separated when pressure is applied in said cylindrical shaft to effect a return stroke thereof. 70

5. In a broaching machine, a pull bushing comprising a head, a pair of broach engaging dogs pivoted in said head, means to move said dogs toward each other to engage the broach, means to which pressure may be applied to produce a return stroke of the bushing, and automatic means, including a member slidable in said head upon the application of pressure to said member and connections between said member and said dogs, to separate the dogs at the beginning of the return movement of the bushing. 80

6. In a broaching machine, a pull bushing comprising a head, a pair of broach engaging dogs pivoted in said head, means to move said dogs toward each other to engage the broach, means to which pressure may be applied to produce a return stroke of the bushing, and automatic means, including a member slidable in said head upon the application of pressure to said member and connections between said member and said dogs, to separate the dogs at the beginning of the return movement of the bushing, and to hold said dogs locked in separated position until manually released therefrom. 90

7. In a broaching machine, a pull bushing comprising a head, a pair of broach engaging dogs pivoted in said head, means to move said dogs toward each other to engage the broach, means to which pressure may be applied to produce a return stroke of the bushing, and automatic means, including a member slidable in said head upon the application of pressure to said member and connections between said member and said dogs, to separate the dogs at the beginning of the return movement of the bushing, and means to manually operate said separating means. 100

8. In a broaching machine, a pull bushing comprising a head, a pair of broach engaging dogs pivoted in said head, means to move said dogs toward each other to engage the broach, means to which hydraulic pressure may be applied to produce a return stroke of the bushing, and means, including a member slidable in said head upon the application of said hydraulic pressure to said member and connections between said member and said dogs, to simultaneously separate said dogs to release the broach at the beginning of the return movement of the bushing. 115

9. In a broaching machine, a pull bushing comprising a head, a pair of broach engaging dogs pivoted in said head, means to move said dogs toward each other to engage the broach, means to which hydraulic pressure may be 130

applied to produce a return stroke of the bushing, and means, including a member slideable in said head upon the application of said hydraulic pressure to said member and connections between said member and said dogs, to simultaneously separate said dogs to release the broach at the beginning of the return movement of the bushing, and means to hold said dogs in separated position after the hydraulic pressure has been relieved.

10 In testimony whereof I have hereunto affixed my signature.

DONALD H. WEST.
